(57) **CLAIM**

The ornamental design for a beam axle as shown and described.

DESCRIPTION

FIG. 1 is a front elevation view of a beam axle showing our new design;

FIG. 2 is a rear elevation view thereof;

FIG. 3 is a top plan view thereof;

FIG. 4 is a bottom plan view thereof;

FIG. 5 is a left side view thereof;

FIG. 6 is a right side view thereof;

FIG. 7 is a top, front and right side perspective view thereof; and,

FIG. 8 is an enlarged view of area 8 of FIG. 7.

The broken lines in the drawing depict portions of the beam axle that form no part of the claimed design.

The dot-dash lines in FIGS. 7 and 8 indicate the boundaries of the enlarged view and are used for annotative purposes only. They do not limit or define the scope of the claimed design.
